UNITED STATES PATENT OFFICE.

REUBEN L. PRICE, OF FORESTBURG, TEXAS.

STALK-CUTTER.

SPECIFICATION forming part of Letters Patent No. 325,628, dated September 1, 1885.

Application filed September 25, 1884. (No model.)

To all whom it may concern:

Be it known that I, REUBEN L. PRICE, a citizen of the United States, residing at Forestburg, in the county of Montague and State 5 of Texas, have invented certain new and useful Improvements in Stalk - Cutters, of which the following is a specification, reference being had therein to the accompanying drawings.

10 This invention relates to certain improvements in stalk-cutters; and it has for its objects to provide a machine which will accommodate itself to the irregularities of the soil over which it is worked, and effectually cut 15 the stalks or stubble in the field, so as to prepare it for plowing, as more fully hereinafter set forth. These objects I attain by the means illustrated in the accompanying drawings, in which—

20 Figure 1 represents a perspective view of my invention, and Fig. 2 a longitudinal vertical sectional view of the same.

In the drawings, the letter A indicates the frame or carriage of the machine, which is 25 mounted upon ordinary wheels, B, being provided with a tongue, C, in front, and having a seat, D, at the rear.

The letter E indicates a frame pivoted within the frame A upon a transverse rod, F. The 30 said frame is provided with a number of apertures, G, through which said rod may be passed in order to adjust the height of said frame. At the lower end of said frame is journaled a shaft, H, having a series of arms, 35 I, carrying cutting-blades K which operate to cut the stalks when the machine is in use. The frame E is also provided with a transverse shaft, L, to which the curved rake-teeth M are attached. These teeth are bifurcated 40 at their free ends to receive the curved points N, which are riveted or bolted in place.

The letter P indicates a lever which is fulcrumed on a cross-bar, R, of the frame E, and whose lower end is connected by means of a 45 link, V, to a lug on the rake-shaft, said lug being located at about a right angle to the point of attachment of the rake-teeth. As the rake-shaft is loosely mounted in frame E it is evident that when the lever is op-

erated the cutter-frame will have no movement until the rake-shaft has made about a quarter-revolution, at which time the lever will commence acting on the frame. Thus it will be seen the rake-teeth are elevated to a certain extent independently of the cutter-frame.

The lever P is held in any desired position by engaging the ratcheted segment S, which is journaled to the platform T, and is provided with a spring foot-lever, J, by means of which it can be thrown into and out of engagement with the lever P.

The rake-teeth are held against the strain of the vegetable material by means of the links W and perforated plates X, which are 65 secured to hooks Y on the frame E. The frame E is also provided with hooks Z, which are secured to the links A' by means of chains B'.

The links A' are connected to the whiffle-tree C', and to the frame at each side, by means of the rods D'.

When in operation the frame E is let down, as shown in Fig. 2 of the drawings, the rake traveling in front of the cutter, so as 75 to rake in the stalks and bring them properly under the action of the cutter-blades, which rotate and thoroughly cut and chop the stalks.

Having thus described my invention, what 80 I claim, and desire to secure by Letters Patent, is—

1. In a stalk-cutter, the combination, with a pivoted cutter-frame bearing revolving cutters, and a rake-shaft provided with rake-teeth, of a lever for moving said frame into and out of working position, and a journaled ratchet-segment with which the lever engages, said segment provided with a spring foot-lever for throwing it out of engagement 90 with the operating-lever, substantially as described.

2. The combination, with a pivoted cutter-frame provided with revolving cutters mounted in a carriage, of a rake-shaft loosely mounted in said frame, rake-teeth attached to said shaft and extending in front of the cutters, and an operating-lever fulcrumed at 95

the upper end of the cutter-frame and connected at its lower end by means of a link with a lug on the rake-shaft at about a right angle to the point of attachment of the 5 rake-teeth, whereby the rake may be elevated independently of the cutter-frame, substantially as described.

In testimony whereof I affix my signature in presence of two witnesses.

REUBEN L. PRICE.

Witnesses:

F. M. WALKER,
W. C. NORRIS.
